UNITED STATES PATENT OFFICE

147,473

DESIGN FOR A RADIO CABINET

Michel C. Rosenthal, New York, N. Y.

Application March 7, 1946, Serial No. 127,175

Term of patent 3½ years

(Cl. D56—4)

To all whom it may concern:

Be it known that I, Michel C. Rosenthal, a citizen of the United States and a resident of the city, county, and State of New York, have invented a new, original, and ornamental Design for Radio Cabinet, of which the following is a specification, reference being had to the accompanying drawing, forming part thereof, in which:

Fig. 1 is a front perspective view of a radio cabinet, embodying my design.

Fig. 2 is a partial vertical section, with parts broken off, of the cabinet of Fig. 1, taken on the line 2—2 of Fig. 3, and

Fig. 3 is a horizontal sectional view of the cabinet shown in Fig. 1.

The rear portion of the radio cabinet embody-

ing my design is similar to the front portion shown in Fig. 1, except for the omission of the tuning dial and of the control knobs.

I claim:

The ornamental design for a radio cabinet, as shown and described.

MICHEL C. ROSENTHAL.
